UNITED STATES PATENT OFFICE.

JOHN D. RAUCH, OF LIMA, OHIO, ASSIGNOR TO THE CAST STEEL DEVICES CO., OF LIMA, OHIO, A CORPORATION OF OHIO.

LOCOMOTIVE FRAME.

Application filed April 30, 1926. Serial No. 105,645.

This invention relates to improvements in cast steel locomotive frames, and has for its principal object to provide a new and improved form of frame capable of being readily cast in a single piece in such form and shape as to accommodate certain parts of the spring and brake rigging and yet affording sufficient strength for a main frame casting itself. The invention may best be understood by reference to the accompanying drawings, in which

Figure 1 is made up of the two-part figures 1 and 1^a which may be placed end to end so as to show the entire length of a single frame member casting.

Figure 2 similarly consists of two part-figures 2 and 2^a which may be placed end to end, and together showing a section taken through the longitudinal center line of the casting.

Figure 3 is made up of two part-figures 3 and 3^a, together forming a plan view of the main frame casting with parts broken away along the upper half of the view to show the several web portions and pedestals in part section.

Figures 4, 5, 6, 7 and 8 are sectional views taken on irregular section lines 4, 5, 6, 7 and 8, respectively of Figs. 3 and 3^a.

In the drawings, the invention is shown as applied to a steam locomotive having four driving axles, although it may be applied to any number of driving axles. The single frame casting 10 is provided with four sets of pedestal recesses formed between guides 12, 12, with the driving axles indicated in dotted lines at 11, 11 in Figure 1. These driving axles form part of the usual running gear, including journal boxes which engage with pedestal guides 12, 12 in the usual manner. The construction of such journal boxes and running gear will be readily understood by those familiar with the art, so are not shown in detail.

It will be manifest that it is inherently difficult to produce a relatively light, but sufficiently strong casting of such a generally irregular shape, especially in view of the plurality of pedestal recesses as shown.

The frame 10 comprises as its main elements two vertically disposed beams or side members 15, 15 which extend the length of the frame, and support the pedestal guides

12, 12 therein. They are joined together at the front end by a cross member 16, and at the rear end by a cross member 17 the latter of which includes a pivotal bearing support 18 for the tender. The side members are also joined by certain other intermediate members of special construction, and will now be described in detail.

Referring now to Figures 2 and 3, it will be seen that the two side walls 15, 15 are somewhat higher at their central portions where they are arched over the pedestal guides 12, 12 and are joined together by four cross pieces 30, 31, 32 and 33. The four cross pieces are spaced apart so that each is disposed over, or adjacent a pair of pedestal recesses. It will clearly appear from Figures 3 and 3^a that all of the cross pieces just referred to are joined to inwardly disposed flanges or webs 34, 34 connected to and forming continuations of the upper edge of the side members 15, 15 so as to form in effect a continuous web arched across the top of the frame at its central raised portion.

A second set of connecting pieces will also be seen in Figure 2, which consists of a plurality of cross members 37, 37 which are shown in cross section curving over the upper corners of the three front pairs of pedestal guides 12, 12 and cross members 38, 38 which are disposed to connect the lower corners of each oppositely-disposed pair of pedestal guides. The adjacent cross members 37 and 38 are joined to flanges or webs 39, 39 extending inwardly from the side members 15, 15 so as to form in effect a second continuous web, comprising all parts 37, 38 and 39, which is thereby arched in longitudinal section over each pedestal recess and thence downwardly and thence across to provide both longitudinal and lateral support between each adjacent pair of pedestal guides. It will now be clear that the first web consisting of the parts 30, 31, 32, 33 and 34, connecting the top of the side frame members 15 are spaced vertically above the second web consisting of parts 37, 38 and 39, so that the two webs together provide a relatively light but rigid construction, particularly effective in providing the required strength for the purpose for which such frame is designed. Obviously, the cross-portions of the two connecting

webs may be made wider or narrower so as to form more or less, continuous webs, as dictated by strength required, or to accommodate associated mechanical parts of the locomotive.

In carrying out my invention, I have also provided means for accommodating equalizing spring rigging of a standard type, such as is shown in dotted lines in Figures 1 and 10 1^a. The parts of the equalizing rigging indicated include two sets or systems, the first set serving the two front axles and including side springs 17^a, 17^a, links 18^a, 18^a and equalizer bar 19, arranged along each side member and connected together by a cross-equalizer bar (not shown) in the usual manner. The second set of equalizing rigging includes springs 21, 21^a, equalizer bars 22, 22, links 23, 23 and any suitable cross-equalizer bar, if desired.

Referring now to the method of accommodating these, or similar spring rigging devices, it will be seen that I provide a plurality of indentations or recesses 25, 25, formed 25 along the upper corners of the side frame members 15, 15 and in which the equalizer springs 17^a and 21 may have movement. These indentations are best recognized in the left hand sectional view, Figure 7, although 30 they can also be seen in Figures 1, 2, 3 and 8. It is usually desirable that the equalizing springs be disposed directly above the journal boxes which are engaged between the pedestal guides 12, 12, and to this end, the 35 equalizing springs 17^a and 21 engage blocks 26, 26, which extend downwardly through slots or apertures 27 formed in the frame at the bottom of their respective recesses 25, 25 in position to engage the top of their journal 40 boxes. Similarly, the inner equalizing links 18^a, 18^a and 23, 23 extend through apertures 28, 28 adjacent the ends of the recesses 25, 25. This provision of recesses 25, 25, and apertures 27 and 28, requires that the center portion of the main frame be made 45 higher in order to gain the required strength over the arched pedestals without unduly raising the height of the equalizing springs 17^a and 21. In the form shown, it will be

seen that the recesses 25, 25, are formed contiguous to flanges 34, 34, and thus form with the side walls of said recesses a continuation of the upper connecting web heretofore described as including flanges 34 and cross pieces 30, 31, 32 and 33, while the cross pieces 55 37, 37 forming part of the lower connecting web are substantially in horizontal alignment with the bottom of recesses 25, 25 (see Figure 7). The frame member is therefore 60 considerably strengthened by the added height of the frame afforded through the provisions of these recesses 25, 25.

While I have shown and described one particular embodiment of my invention, it will be understood that I do not wish to be 65 limited to the exact construction shown and described, but that various changes and modifications may be made without departing from the spirit and scope of my invention.

I claim as my invention:

1. A locomotive frame comprising a single piece casting having a pair of side members with a plurality of pedestal recesses formed 75 therein, and connecting means for said side members including a web connecting the upper margins of said side members, and a second substantially continuous web arched in longitudinal section over the upper corners of said pedestal recesses and thence 80 downwardly and along the bottom of said side members between adjacent recesses.

2. A locomotive frame comprising a single piece casting having a pair of side members with a plurality of pedestal recesses 85 formed therein, and connecting means for said side members including a substantially continuous web connecting the upper margins of said side members, and a second substantially continuous web extending over, 90 and downwardly along the sides of each of said pedestal recesses, and from thence along the bottom of said side members between adjacent pairs of recesses.

Signed at Lima, O., this 27th day of April, 1926.

JOHN D. RAUCH.
